US0D1024089S

(12) **United States Design Patent** (10) **Patent No.:** **US D1,024,089 S**
(45) **Date of Patent:** **** Apr. 23, 2024**

(54) **DISPLAY SCREEN OR PORTION THEREOF WITH GRAPHICAL USER INTERFACE**

(71) Applicant: **Salesforce, Inc.**, San Francisco, CA (US)

(72) Inventors: **Puneet Dhaliwal**, Hayward, CA (US); **Niv Garber**, Petah Tikva (IL); **D. Dustin Breese**, San Francisco, CA (US); **Prithvi Krishnan**, **Padmanabhan**, San Ramon, CA (US); **Kara Carreri**, Atlanta, GA (US); **Rahul Mehta**, San Francisco, CA (US); **Raghav Abboy**, San Francisco, CA (US); **Yongbo Zuo**, San Francisco, CA (US); **Abraham Reyes**, Atlanta, GA (US)

(73) Assignee: **Salesforce, Inc.**, San Francisco, CA (US)

(**) Term: **15 Years**

(21) Appl. No.: **29/768,475**

(22) Filed: **Jan. 29, 2021**

(51) LOC (14) Cl. **14-04**

(52) U.S. Cl.

USPC **D14/485**

(57) **CLAIM**

The ornamental design for a display screen or portion thereof with graphical user interface, as shown and described.

DESCRIPTION

FIG. 1 is a front view of a display screen or portion thereof with graphical user interface, showing a first image of the claimed design;

FIG. 2 is a second image thereof;

FIG. 3 is a third image thereof; and,

FIG. 4 is a fourth image thereof.

The outermost dashed broken lines in FIGS. 1-4 show a display screen or portion thereof, and form no part of the claimed design. The other dashed broken lines in FIGS. 1-4 show text, graphics, and other elements that form no part of the claimed design.

1 Claim, 4 Drawing Sheets
